7 Claims. (Cl. 171—327)

1

My present invention relates to improvements in piezoelectric means for converting pressure variations into potential variations, as applied in particular for measuring the pressure variations in the cylinders of internal combustion engines. In such piezoelectric means the quartz system, which is prestressed in the direction of pressure, is arranged in form of a rod and incorporated in a metallic sleeve which is closed on the side of the pressure chamber.

In accordance with comparatively recent fundamental investigations, it is possible to construct piezoelectric units of particularly high accuracy by very rigidly bracing the pressure-responsive quartz elements, and by resiliently prestressing the said elements in the direction of the pressure.

Quartz units built on the basis of the above-cited conditions and which comprise two bored centrally prestressed quartz plates, however, have a disadvantage in that they are not reliable in operation, since they cannot be sufficiently sealed against penetration of combustion gases and moisture.

In order to obviate such disadvantage, quartz units are known in the art in which the quartz plates are accommodated in a metallic sleeve which is closed on the side facing the pressure chamber, such sleeve at the same time acting to elastically prestress the quartz plates. The resilience of this wide and relatively short sleeve, however, is too small, from which reason piezoelectric means of such latter type are temperature-sensitive and only slightly pressure-responsive. It is conceded, however, that such latter type piezoelectric means has an advantage in that an axial bore may be used for delivering the electrical charge.

It is known on the other hand that quartz elements in form of rods are more highly pressure-responsive than elements in form of plates. In piezoelectric units provided with such quartz rod, the latter is pressed in direction of the normal crystal axis, and the arising electrical charge is taken off the two sides of the rod, as schematically shown in Fig. 1. The correct bracing and prestressing of such quartzes, however, presents even greater difficulties, especially as lateral bores have to be provided in the casing for carrying off the electrical charge.

The said disadvantages are eliminated in accordance with my present invention, in that at least two juxtaposed quartz rods are provided in the piezoelectric unit, which rods together form a cylinder. The said rods are so cut from the crystal that their neutral axes run parallel to

2

the pressure axis and their electrical axes are poled against each other and stand at right angles to the direction of pressure. The quartz rods are prestressed in the direction of pressure, and accommodated in a metallic sleeve which is closed on the side of the pressure chamber.

One form of my present invention is shown in the accompanying drawing, in which—

Fig. 1 a perspective view of a prior-art quartz unit in form of a solid rod as cited above,

Fig. 2 a perspective view of a quartz unit according to my present invention, comprising a pair of juxtaposed semi-cylindrical quartz rods,

Fig. 3 a longitudinal section through the piezoelectric means, and

Fig. 4 a modified sleeve mount for the quartz unit.

As shown in Fig. 2, the pressure-responsive unit comprises two juxtaposed semi-cylindrical quartz rods 1 and 2 which together form a cylinder. The said rods are so cut from the quartz crystal that their neutral axes 3 run parallel to the pressure or cylinder axis and their electrical axes 4 have opposite poles and stand at right angles to the plane of separation. In this manner only positive charges, e. g., are set up on the curved surfaces of the two rods, and only negative charges are set up on the plane adjacent faces, as soon as a pressure is exerted on the rods.

As shown in Fig. 3, the two prestressed quartz rods 1 and 2 are suitably accommodated in a thin-walled sleeve 5 and abut against the steel cylinders 6 which are force fits in the said sleeve. The quartz rods are cut from the crystal so that their neutral axes run parallel to the pressure axis and their electrical axes have opposite poles and stand at right angles to the plane of separation.

The upper, conically tapered end of the sleeve 5 is fitted in the respective conical bore of the casing 7. The lower end 5b of the sleeve, which is enlarged mushroom-like and which has to take up the gas pressure, is formed on its border with a thin diaphragm 8. The peripheral bead of the latter is rolled gastight in the foot of the casing 7.

The charge produced on the curved surface of the quartz cylinder when stressing the latter in the longitudinal direction, which charge e. g. may be positive, is earthed through the sleeve. The charge arising in the interior of the cylinder at the plane of separation, which charge e. g. may be negative, is taken up through a thin copper strip 9 and fed through the conductor 10 to the contact 11 which is lodged in the amber insulator

bushing 12. If required, coolant water may be supplied to the piezoelectric means through the pipes 13. The drying substance 14 serves for abstracting any moisture which may have been introduced. The said substance is so disposed in the piezoelectric means that moisture which may have penetrated from the coolant chamber through the sealing faces into the quartz chamber, is adsorbed.

When pressure arises on the diaphragm 8, it is transmitted onto the quartz rods as well as onto the sleeve 5. The said rods are slightly compressed in accordance with their modulus of elasticity. The thin-walled sleeve 5 which is prestressed in the longitudinal direction, will be relieved or distended in the same measure and elastically shortened. If the sleeve portion 5a had a substantial wall thickness, it would take up practically all of the pressure exerted on the diaphragm 8, and only a very small portion of the pressure would be transmitted onto the quartz cylinder. The piezoelectric means, therefore, would not readily respond to pressure fluctuations and, thus, would be more sensitive to temperature. Since, however, the wall 5a of sleeve 5 is extremely thin, it absorbs only a few percent of the pressure exerted on the diaphragm 8. By reason of the prestress applied to sleeve 5, substantial tensile stresses and elongations are set up in the portion 5a of the sleeve.

In the modified sleeve structure 15 shown in Fig. 4, the sleeve portion 15a surrounding the quartz cylinder is not formed as cylindrical thin wall, but is corrugated. Such construction gives the sleeve portion 15a a higher elasticity in the longitudinal direction, whereby its wall 15a may be made thicker than in the first case.

What I claim as new and desire to secure by Letters Patent is:

1. In a piezoelectric means for converting pressure variations, in particular in the cylinders of internal combustion engines, into potential variations, in which the quartz unit is prestressed in the direction of pressure and is formed as rod and incorporated in a metallic sleeve which is closed on the side of the pressure chamber, a quartz unit comprising at least two juxtaposed

4
semi-cylindrical quartz rods which are so cut from the crystal that their neutral axes run parallel to the pressure axis and their electrical axes have opposite poles and stand at right angles to the direction of pressure.

2. In a piezoelectric means as set out in claim 1, an electrically conductive thin strip inserted in the surface of separation of the quartz rods, the said strip being adapted to take up the electrical charge arising on application of pressure and to deliver the same to an electric conductor.

3. In a piezoelectric means as set out in claim 1, including ducts for coolant water, a quantity of drying substance lodged intermediate the coolant chamber and the quartz rods so that any leakage of traces of coolant first reaches the drying substance before passing to the quartz rods.

4. In a piezoelectric means as set out in claim 1, a quartz unit in which the sleeve portion surrounding the quartz rods is formed axially yieldable so as to be capable of elastically yielding to the pressure acting from the pressure chamber onto the sleeve end.

5. In a piezoelectric means as set out in claim 4, a quartz unit in which the sleeve portion surrounding the quartz rods is corrugated to attain the desired resilience.

6. In a piezoelectric means as set out in claim 4, an element for axially prestressing the quartz rods and comprising at least one axially bored cylinder adapted to be pressed into the open sleeve end so as to hold the quartz rods rigidly in the sleeve end, and, on the other hand to prestress the elastic sleeve portion.

7. In a piezoelectric means set out in claim 4, a sleeve of which the portion surrounding the quartz rods is made extremely thin for the purpose of attaining the desired resilience.
